To all whom it may concern:

Be it known that I, Helen Neumann, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

I claim:

The ornamental design for a dress, substantially as shown and described.
